UNITED STATES PATENT OFFICE.

JOHN JOSEPH BERRIGAN, OF AVON, NEW YORK, ASSIGNOR TO THE DE
LAVAL SEPARATOR COMPANY, OF NEW JERSEY.

DEVICE FOR ASSEMBLING OR DISASSEMBLING THE PARTS OF CENTRIFUGAL LIQUID-SEPARATORS.

SPECIFICATION forming part of Letters Patent No. 663,114, dated December 4, 1900.

Application filed June 29, 1900. Serial No. 22,042. (No model.)

To all whom it may concern:

Be it known that I, JOHN JOSEPH BERRIGAN, a citizen of the United States, residing at Avon, county of Livingston, and State of New York, have invented a new and useful Improvement in Devices for Assembling or Disassembling the Parts of Centrifugal Liquid-Separators, of which the following is a full, clear, and exact description, reference being had to the accompanying drawings, which form a part of this specification.

My invention relates to that class of centrifugal liquid-separators in which the interior of the bowl is subdivided into a plurality of strata, both radially and vertically, by means of superposed inclined division rings or disks. These rings or disks may be supported in the bowl in different ways. For example, they may be supported upon the hollow shaft central of the bowl through which the liquid to be separated enters the bowl. In case the disks are supported upon the hollow shaft it may be done by providing each of the rings or disks with a series of notches or orifices which register with radial projections from the hollow shaft. With machines using these disks or rings considerable difficulty is experienced in removing the disks or rings to clean them. Difficulty is also experienced in replacing the disks or rings properly in the bowl.

The object of my invention is to provide means whereby the disks can be removed from the bowl, separated for cleaning purposes, and replaced in the bowl with ease and despatch and without necessarily manipulating the disks individually in the operation of removal and replacement.

The invention consists generally of a removing, retaining, and replacing device capable of being adjusted to the bowl and having guiding and engaging means which may be aligned or registered with complementary means on the disks, whereby the disks in the operation of removal from the bowl will engage the said device and may then be slid longitudinally along the device independently, while being held from rotation thereupon.

More specifically, the invention consists of a removing, retaining, and replacing device capable of being adjusted to the bowl and

having guiding and engaging means which may be aligned or registered with means on the disks which engage one or more of the 55 disk-supporting devices in the bowl, and whereby the same results are accomplished. In this construction the engaging and guiding means on the removing, retaining, and replacing device will align and register with 60 the said disk-supporting device or devices in the bowl, the means on the disks whereby the disks engage the said disk-holding device or devices in the bowl performing also the function of engaging the engaging and guiding means on the removing, retaining, and replacing device in the process of removing the disks from the bowl.

More narrowly considered, it consists of a construction wherein the engaging and guiding means on the removing, retaining, or replacing device consists of a rod or rods which are of such shape that they can readily enter the orifices or notches in the disks, which engage the disk holding or supporting device 75 in the bowl. The tube or rod to which this rod or series of rods are connected is of such construction that it is adapted to interlock with the hollow shaft, enabling the device to be brought to and maintained in proper position with reference to the notches or orifices in the disks, so that the rod or rods will register with said notches or orifices. When this position is reached, the disks or rings may be readily removed from the bowl by 85 sliding them upon the rod or rods. When so removed, any means may be adapted to lock them from slipping off either end of the rod or series of rods. In practice the rod or series of rods will be of greater extent than the 90 vertical space occupied by the disks in the bowl, and thus the disks or rings may be spread out on these rods for cleaning purposes. To replace these disks or rings in the bowl, it is only necessary to again place the 95 device in proper position with reference to the bowl and then move the disks or rings from the rod or rods to their place in the bowl.

I will now describe the embodiments of my invention illustrated in the accompanying 100 drawings, in which—

Figure 1 is a side elevation of the tubular shaft, the disks or rings, and the removing and replacing device. Fig. 2 is a similar

view, inverted, with the disks or rings transferred to the removing and replacing device. Fig. 3 is a side elevation of the removing and replacing device with the disks or rings thereon and with its handle. Fig. 4 is a detail section on line 4-4, Fig. 1. Fig. 5 is a modified form of removing and replacing device. Fig. 6 is a sectional view of same.

A is the tubular shaft of a centrifugal liquid-separator having the projections *a* beveled at their upper ends *a'*.

B shows a series of inclined disks or rings provided with the orifices *b*. These disks or rings are superposed one upon the other by being held upon the projections *a* through the medium of orifices *b*.

C is the removing and replacing device, composed of the following parts: C' is a head, to which are secured the rods *c*, equal in number to the orifices *b* in the disks, and having their lower ends beveled at *c'*, corresponding to the bevel *a'* of the projection *a*.

D D' are braces, to the exterior of which the rods *c* are connected and by which the rods *c* are held in a fixed position relative to each other—that is, cannot spring in or out.

E is a rod or tube extending from the brace D'. This rod E is of such size as to be capable of insertion and movement in the tubular shaft A. The size and position of the brace D', the position of the projections *a*, and their size and the distance of the rod E below the brace D' are such that, as shown in Fig. 1, when the rod E is inserted and forced down in the tubular shaft A the projection D' will seat on the end of the shaft A and the rods *c* register with the orifices *b*. Under this condition the shaft A and the removing and replacing device C are reversed, as shown in Fig. 2, and the disks or rings pushed from the shaft A to the device C, which may then be removed from its connection with the shaft A. In order to interlock the removing device with the shaft during the transfer of the disks or rings, I provide a pin *e* in one of the rods *c*, which registers with an orifice *e'* in the corresponding projection *a*. When the device C is removed from the shaft A, the disks or rings may be placed apart upon the device C to enable the disks to be readily cleaned.

In order to prevent the disks or rings passing off either end of the rods *c* and to provide a ready means to hold the device C during the washing of the disks or rings, I provide the following construction: Through the rod E, the braces D' and D, and the head C' is an orifice through which passes the spring-arm *f* of the handle F. This arm *f* is free at one end, where it may be interlocked with the remainder of the handle through the medium of the loop *f'*. After the device C has been removed from the shaft A the member *f* of the handle F may be inserted and locked, as described, the disks or rings spaced apart, and the handle used to hold the device to facilitate the cleaning of the disks or rings.

Instead of constructing the removing and replacing device with a plurality of rods equal in number to the orifices *b*, I can use a single guiding-rod *c*, which will register with one of the orifices *b*. This guiding-rod *c* is projected from a hollow cylinder L, which is adapted at its lower end to surround and interlock with the shaft A.

Having now fully described my invention, what I claim, and desire to protect by Letters Patent, is—

1. A device for removing and replacing disks or rings of a centrifugal separator of the character described, consisting essentially of a guiding and supporting device adapted to register with and form a prolongation of the disk-supporting device.

2. A device for removing and replacing disks or rings of a centrifugal separator, of the character described, consisting essentially of a guiding and supporting device adapted to register with orifices in the disks and with the shaft.

3. A device for removing and replacing disks or rings of a centrifugal separator of the character described, provided with a guiding and supporting device adapted to register with a disk-supporting device and a support for said guiding and supporting device adapted to register with the shaft.

4. A device for removing and replacing disks or rings of a centrifugal separator of the character described, provided with a guiding and supporting device adapted to register with orifices in the disks and a support for said guiding and supporting device adapted to register with the shaft.

5. A device for removing and replacing disks or rings of a centrifugal separator of the character described, consisting essentially of an extended support, having different parts of its periphery in cross-section at different radial distances from the longitudinal axis of the support, and adapted to register with and form a prolongation of the disk-supporting device.

6. A device for removing and replacing disks or rings of a centrifugal separator of the character described, consisting essentially of an extended support, having different parts of its periphery in cross-section at different radial distances from the longitudinal axis of the support, and adapted to register with the disks and with the shaft.

7. A device for removing and replacing disks or rings of a centrifugal separator of the character described, consisting essentially of a main body portion and a projecting longitudinal portion adapted to register with the disks.

8. A device for removing and replacing disks or rings of a centrifugal liquid-separator, of the character described, consisting essentially of a plurality of rods spaced apart adapted to register with the disk-supporting devices.

9. A device for removing and replacing disks or rings of a centrifugal liquid-separator, of the character described, consisting essentially of a plurality of rods spaced apart 5 adapted to register with the disk-supporting devices, and a device adapted to register with the shaft.
10. A device for removing and replacing disks or rings of a centrifugal liquid-separator, of the character described, consisting essentially of a plurality of rods spaced apart 10 adapted to register with the projections on the tubular shaft.
11. A device for removing and replacing 15 disks or rings of a centrifugal liquid-separator of the character described, consisting essentially of a plurality of rods spaced apart adapted to register with the projections on the tubular shaft, and a central rod adapted 20 to enter said tubular shaft.
12. The combination with a device for removing and replacing disks or rings of a centrifugal liquid-separator of the character described, consisting essentially of a plurality 25 of rods spaced apart adapted to register with the disk-supporting devices, of a handle removably connected with said device.
13. The combination with a device for removing and replacing disks or rings of a centrifugal liquid-separator, of the character described, consisting essentially of a plurality 30 of rods spaced apart adapted to register with the disk-supporting devices, and a device adapted to interlock with the tubular shaft, 35 of a handle removably connected with said removing and replacing device.
14. The combination with a device for removing and replacing disks or rings of a centrifugal liquid-separator of the character described, consisting essentially of a plurality 40 of rods spaced apart adapted to register with the projections on the tubular shaft, of a handle removably connected with said device.
15. The combination with a device for removing and replacing disks or rings of a centrifugal liquid-separator of the character described, consisting essentially of a plurality 45 of rods spaced apart adapted to register with the projections on the tubular shaft, and a central rod adapted to enter said tube and shaft, of a handle removably connected with said device.
16. A device for removing and replacing disks or rings of a centrifugal liquid-separator 55 of the character described, consisting essentially of a plurality of rods spaced apart and having their lower ends beveled to correspond to the bevel upon the projection on the tubular shaft of the machine and a central 60 rod adapted to enter said tubular shaft.
17. A device for removing and replacing disks or rings of a centrifugal liquid-separator of the character described, consisting essentially of a plurality of rods spaced apart 65 adapted to register with the projection on the tubular shaft of the machine, a central rod adapted to enter said tubular shaft and a pro- jecting surface on the end of said rod adapted to be seated on the end of said tubular shaft.
18. A device for removing and replacing 70 disks or rings of a centrifugal liquid-separator, of the character described, consisting essentially of a plurality of rods spaced apart adapted to register with the projections on the tubular shaft and a central rod adapted 75 to enter said tube and shaft, there being an orifice through the length of said central rod.
19. A device for removing and replacing disks or rings of a centrifugal liquid-separator of the character described, consisting essentially of a plurality of rods spaced apart 80 adapted to register with the projection on the tubular shaft of the machine, a central rod adapted to enter said tubular shaft and a projecting surface on the end of said rod adapted 85 to be seated on the end of said tubular shaft, there being an orifice through the length of said central rod and said projecting surface.
20. The combination with a device for removing and replacing disks or rings of a centrifugal liquid-separator, of the character described, consisting essentially of a plurality 90 of rods spaced apart adapted to register with the projections on the tubular shaft and a central rod adapted to enter said tube and 95 shaft, there being an orifice through the length of said central rod, of a handle one member of which passes through said orifice and interlocks with the remainder of the handle. 100
21. A device for removing and replacing disks or rings of a centrifugal liquid-separator of the character described, consisting essentially of a plurality of rods, provided with braces to space them apart, adapted to register with the projection on the tubular shaft, and a central rod adapted to enter said tubular shaft, said braces being adapted to seat upon the end of said tubular shaft, there being an orifice through the length of said central rod and through said braces. 110
22. The combination with a device for removing and replacing disks or rings of a centrifugal liquid-separator of the character described, consisting essentially of a plurality 115 of rods, provided with braces to space them apart, adapted to register with the projection on the tubular shaft, a central rod, extending from one of the braces, and adapted to enter said tubular shaft, said brace being adapted 120 to seat upon the end of said tubular shaft, there being an orifice through the length of said central rod and through said braces, of a handle one member of which passes through said orifices and interlocks with the remainder of the handle. 125
- In testimony of which invention I have hereunto set my hand, at New York, N. Y., this 25th day of June, 1900.
